UNITED STATES PATENT OFFICE.

EDWARD B. WALSH AND WILLIAM SCHRIER, OF LOS ANGELES, CALIFORNIA.

FOLDING HOD.

1,325,820.

Specification of Letters Patent. Patented Dec. 23, 1919.

Application filed August 20, 1919. Serial No. 318,756.

To all whom it may concern:

Be it known that we, EDWARD B. WALSH and WILLIAM SCHRIER, citizens of the United States, residing at Los Angeles, in the county of Los Angeles, State of California, have invented a new and useful Folding Hod, of which the following is a specification.

It is one object of this invention to provide a hod which may be folded up readily into small compass when not in use. Another object of the invention is to provide novel means for holding the constituent parts of the hod together.

15 A further object of the invention is to provide novel means for retaining a drip trough in place on the hod.

It is within the province of the disclosure to improve generally and to enhance the 20 utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the 25 invention shown can be made without departing from the spirit of the invention.

In the accompanying drawings:—

Figure 1 shows in side elevation, a hod constructed in accordance with the invention; Fig. 2 is a longitudinal section of the hod; Fig. 3 is a transverse section of the hod; Fig. 4 is a bottom plan of the hod; and Fig. 5 is a perspective showing a portion of the end wall of the hod.

40 The hod forming the subject matter of this application preferably is made of metal and includes sides 1 having overlapped end flanges 2 and bottom flanges 3, the flanges 3 carrying coöperating knuckles 4 through which a pivot rod 5 passes, the rod having an enlarged head 6 at the discharge or open end of the hod. The sides 1 are provided with marginal beads 7 in which reinforcing rods 18 are located, the reinforcing rods 45 projecting beyond the beads and being fashioned into eyes 8 surrounding the pivot rod 5 at the open end of the hod and serving to space outwardly, the head 6 on the pivot rod, so that this head serves as a bumper used when the hod is struck against an object to discharge the load in the hod. That

end of the pivot rod 5 which is remote from the head 6 carries a nut 9. The numeral 10 denotes a drip trough wherein the lower edges of the sides 1 are received, the drip trough terminating short of the discharge end of the hod, as delineated in Fig. 1. The drip trough 10 includes an end wall 11 through which the extremity of the pivot rod 5 passes, the nut 9 on the pivot rod 60 bearing against the end wall. The drip trough, therefore, is held in place on the hod, in part, by the pivot rod 5 and the nut 9. The drip trough 10 is supplied with a shoulder rest 12.

70 The hod includes an approximately triangular end member 14 having a reinforcing top flange 15 and projecting side flanges 16 coöperating with the end flanges 2 of the sides 1 of the hod. Angle brackets 17 75 are secured to the end member 14, and are provided with openings 18. A securing device 19 such as a curved bolt, passes through the openings 18 of the angle brackets 17 and through the flanges 2 of the sides 1, 80 the bolt being provided at one end with a head 20 engaging one side 1. A nut 21 is threaded on the other end of the bolt and coöperates with the other side 1. At this point it should be observed that the extreme lower end of the member 14 is received within the end wall 11 of the drip trough 10, the drip trough and its end wall serving to prevent the lower end of the member 14 from swinging outwardly on the securing 85 device 19.

90 One side 1 of the hod is supplied with a socket 22, open at its end, the other side member of the hod being provided with a V-shaped retainer 23 which is open laterally. An attaching device, such as bolt 24, carrying a nut 25, is mounted within the contour of the retainer 23 and is carried by the corresponding side of the hod. A handle is provided, the same including a fork 100 26 having an arm 27 adapted to be inserted into the socket 22, and an arm 28 adapted to be received in the retainer 23, the bolt 24 passing through the arm 28 and the nut 25 engaging the said arm. The handle includes, further, a staff 29 having a threaded stud 30 engaged detachably with the shank of the fork 26.

110 When it is desired to collapse or fold up the hod, the bolt 24 is removed from the arm 28 of the fork 26, the arm 27 being withdrawn from the socket 22. The staff 29

- may be detached from the fork 26, if desired, since these parts are connected by the threaded stud 30 on the staff. The securing device 19 may be removed, the end member 5 19 may be detached, and the sides 1 may be folded together, the drip trough being held loosely in place, since the end wall 11 of the drip trough is mounted on the pivot rod 5.
- 10 It is to be observed that the drip trough 10 rests in the fork 26. The fork 26, therefore, serves to retain the drip trough in the position shown in Fig. 1 of the drawings. Liquid exuding from the hod is received 15 by the drip trough and is carried toward the rear or open end of the hod, it being impossible for the liquid to ooze down on the hod carrier. The end wall 11 of the drip trough 10 exercises a number of functions.
- 20 It constitutes a washer for the nut 9: it acts as a retainer for the lower end of the member 14: and it prevents the liquid from dripping out of the hod adjacent to the wall or end member 14.
- 25 Having thus described the invention, what is claimed is:—
1. A hod comprising sides; a drip trough receiving the lower edges of the sides and

including an end wall; an end member co-operating with the sides; securing means 30 uniting the end member with the sides, the lower extremity of the end member coöperating with the end wall of the trough to prevent the end member from swinging outwardly on the securing means; a pivot rod 35 whereon the sides are mounted, the pivot rod being engaged with the end wall of the trough; and a handle comprising a fork detachably engaged with the sides, the trough being supported in the fork. 40

2. A hod comprising sides having beads; a pivot rod uniting the sides and provided with a head; and reinforcing rods in the beads, the rods being fashioned into eyes which receive the pivot rod, the eyes coöperating with the head to space the head from the sides of the hod, whereby the head will serve as a bumper. 45

In testimony that we claim the foregoing as our own we have hereto affixed our signatures in the presence of two witnesses. 50

EDWARD B. WALSH.
WILLIAM SCHRIER.
